Howard J. Webster,

W. G. Brown.

Attorney

UNITED STATES PATENT OFFICE.

HOWARD J. WEBSTER, OF PHILADELPHIA, PENNSYLVANIA.

FURNACE-GRAVE BAR.

Application filed September 23, 1924. Serial No. 739,297.

To all whom it may concern:

Be it known that I, HOWARD J. WEBSTER, a citizen of the United States, residing at Philadelphia, in the county of Philadelphia and State of Pennsylvania, have invented 5 certain new and useful Improvements in Furnace-Grate Bars, of which the following is a specification.

This invention relates to grate bars for 10 and used in conjunction with fuel chambers of furnaces, and more especially steam boiler furnaces, and is an improvement of the invention broadly claimed in my former U. S. Patent, No. 1,464,190, dated August 15 7, 1923.

The objects of the invention are:

First, to construct a grate bar which is particularly adapted for burning smaller sizes of anthracite and other low grade fuel 20 at a high rate of combustion.

Second, to so construct and arrange a series of slits within recesses between grids formed in the upper surface of the grate bar as to produce and deliver a series of 25 separated fan-shaped jets of air through the fuel bed which do not in any way elevate a low grade fuel above said bed and supply the requisite amount of air for a high rate of combustion.

Third, to so construct and arrange the recesses or depressions in the upper grate bar surface and the slits within the recesses as to not only give the fan-shaped air delivery jets a greater distance to spread before meeting the fuel bed but at the same 35 time the ash pockets formed by said recesses properly protect the upper surface of the grate bar adjacent the highly heated fuel supported by said grate bar.

Fourth, to construct and dispose the recesses in the upper surface of the grate bar and arrange the slits in said recesses so that the action of a slicing bar or other furnace firing device upon the fuel will not 45 force, pack or embed the fine dust of the fuel or ashes into said slits or recesses, thereby destroying the proper combustion of the fuel and efficient operation of the furnace.

Fifth, to so construct and arrange the 50 elements comprising the grate bar, in order to eliminate the commonly used pin hole nozzle arrangement and consequent diverging projected jet action of the air through the fuel bed, which projected jets of air set up a reverse vortex action causing the light fuel to be elevated far above the fuel bed

level and into the combustion space and forming a series of geysers until finally sections of the fuel bed burn into holes without fuel, thereby destroying the uniform, maximum and efficient combustion of said fuel for a given area of grate surface. 60

Sixth, to construct a grate bar which will tend to preserve a uniform thickness of fuel bed throughout the grate area, and at the same time a constant air pressure in the ash pit, and said air pressure being only varied to change or control the rate of combustion of the fuel. 65

Seventh, to construct and arrange a series of connected grids forming the upper or fire surface of a grate bar so that each of said grids is provided on its underside with a depending rib adapted to convey the heat from the fire surface of each grid down to the cooler air space in the ash pit of the furnace, thereby preventing the grids or grate bars from becoming overheated. 70

Eighth, to construct and arrange a series of connected grids forming the upper or fire surface of a grate bar so that each of said grids is provided on its upper surface with a plurality of specially disposed and arranged longitudinal depressions which 75 operate with a herring-bone rib on the underside of each grid to permit the fire surface of the grate or the top or tie-section of each rib formed by the fire surface of the grid to readily bend and adapt itself 80 to the expansion and contraction of the herring-bone ribs. 85

Ninth, to connect the herring-bone ribs of the end sections or grids of the grate bar to the transverse flange ends of the grate bar so that the end ribs will not burn out 95 should the same become buried in ashes and deprived of air circulation and the intense heat above the grid is transmitted to said end sections.

Tenth, other objects and advantages of 100 the invention will appear from the detailed construction and arrangement of parts and mode of operation to be hereinafter given.

The invention consists of structural characteristics and relative arrangement of elements of parts and mode of operation to be hereinafter more fully described and particularly pointed out in the appended claims. 105

In the drawing, in which similar reference characters indicate the same parts in the 110 several figures:

Figure 1 is a top plan view of a furnace

and partly broken away with two of the improved grate bars in position.

Figure 2 is a longitudinal vertical section on line II—II of Figure 1.

5 Figure 3 is an enlarged end view of one of the grate bars, and

Figure 4 is an enlarged sectional view taken on the line IV—IV of Figure 1.

Referring to the drawings, 10 and 11 are 10 respectively the front and rear walls of a fuel chamber provided with the usual grate bar supports 12 and 13, commonly used in connection with this class of devices and form no part of the present invention.

15 14 is one of the series of grate bars sustained on said supports 12 and 13 and having the upper or fire surface section 15 and the longitudinal ribs 16 for strengthening and stiffening said bar 14, said ribs 16 being cut away at their outer and under edges to form ledges 161 adapted to rest on said supports 12 and 13.

20 The upper or fire surface section 15 of the grate bar is sub-divided into a plurality or 25 a series of grids 17 separated by elongated narrow depressions or recesses 18 which are preferably arranged transversely of the longitudinal axis of said grate bar 14, and extend to within a short distance of the upper 30 edges of the sides 19, 19, as shown in Figure 35 1. Said recesses or depressions 18 are also preferably semi-circular in cross-section in a longitudinal plane normal to the upper fire surface 15 and rounded at their ends 20, as illustrated in Figure 1.

40 Each of said depressions or recesses 18 in the grids 17 is provided with a slot or elongated opening 21 extending transversely and entirely across the upper or fire surface section 15 from one side 19 to the other side 19, and from the bottom of each of said depressions or recesses 18 to and through the underside surface or face 22 of the grids 17 or upper fire surface section 15, as shown in 45 Figure 4, for purposes to be hereinafter described.

50 The middle portions 23 of the sides 19, 19 of the grate bar are slightly enlarged or bulged out, as shown in Figures 3 and 4 for 55 properly spacing adjacent grate bars with respect to each other and forming a narrow air space between the sides 19 and ribs 16 of the bars.

55 The upper face of each grid 17 or the upper fire surface section 15 is formed with a plurality, preferably three, a middle and two side longitudinal depressions 24, 24, which are arranged normal to the depressions or recesses 18, 18, as clearly shown in 60 Figure 1 and extend through and between the front and rear ends of the grate bar for purposes to be presently disclosed.

65 On the under surface 22 of each grid 17 and interposed between the lower openings of the slits 21 is a depending rib or web 25,

preferably of the herring-bone type, said ribs or webs 25 connect the longitudinal ribs 16 with each other, as clearly shown in Figures 1 and 2, and have the function and are particularly adapted to convey the heat 70 from the upper or fire surface 15 of said grid down to the cooler air space in the ash pit and prevent the grids 17 or grate bar 14 from becoming overheated, thereby preventing sagging and burning out, said depending ribs or webs 25 are herring-bone in shape and arrangement for the purpose that said ribs 25 may have, in view of the disposition of the longitudinal depressions 24, 24 with respect to said herring-bone ribs 25, three 80 points of flexure due to a reduction of the T-shaped cross section where the longitudinal depressions 24, 24 cut the grids 17 above the herring-bone ribs 25, and hence permits the ribs or webs 25 to slightly flex to take up the expansion or contraction and hence prevent their cracking.

Furthermore an additional function of 90 said ribs 25, 25 is manifest in that the ribs support the top of the grids and make them stronger to prevent sagging or resist blows from firing tools in case it is required to use force to detach or remove clinker formation fused to the grate bar.

95 The herring-bone ribs of the two end grids of each grate bar 14 is preferably connected to the transverse flanged ends by means of a central longitudinal supporting rib 26 or 27, which rib prevents the end transverse rib from burning out for reasons 100 previously explained, and gives an additional support for the fire surface section 15 of the two end grid sections 17, as will be readily understood and needs no further disclosure.

105 The parts being constructed and arranged as shown with a bed of fuel resting on the upper or fire surface section 15, when a draft of air is passing from the ash pit and upward through the slits 21 in the grate bar, 110 said air issues from the slits and is delivered in fan-shaped jets through the fuel bed without disturbing or raising the low grade or fine fuel from the grate bar, and at the same time insuring a proper and uniform 115 supply of oxygen over the entire grate for a high and quick rate of combustion, thereby effecting a greater capacity or horsepower per square foot of grate surface than with grate bars in which the air is fed through 120 circular openings or pin hole nozzles.

125 As previously explained, the herring-bone ribs of webs 25, 25 most efficiently keep down the temperature of the entire fire surface of the grate bars so that long life and efficient operation of the grate is effected and assured under all conditions of service and permits an intensive firing of the furnace for a short period at the peak of the load, or when it is necessary to briefly over- 130

load the boiler furnace should such an operation be suddenly required in the steam plant.

It will also be seen that when a slicing bar or other firing tool is applied to the fuel bed, said bar will necessarily be required to rest on the upper surface of the grate bar and will thereby be prevented from forcing, packing or embedding the fine fuel or ashes into the slits 21 or recesses 18, thereby insuring a constant and uniform feed of air and combustion of fuel at all times throughout the entire area of the grate surface.

From the foregoing description of the construction and arrangement of parts and mode of operation, it will be readily seen that a grate bar has been devised which comprises a minimum number of highly efficient cooperating elements of simple construction, which can be cheaply manufactured and readily installed or assembled or disassembled or renewed at a minimum of expense and without the use of skilled labor or special tools.

25 It will also be seen that all the objects and advantages recited in the statement of invention have been fully carried out, and while the preferred form has been shown and described, it is to be understood that 30 many changes will suggest themselves without in any way changing the material features of construction or departing from the spirit of the invention as expressed in the claims.

35 What I claim is:

1. A furnace grate bar having a fire surface section provided with a series of separated transverse depressions or recesses in its upper face, a continuous slit in each of 40 and extending the entire length of the depressions or recesses of the fire surface section and extending through the under face of the fire surface section, and a plurality of separated longitudinal depressions in said fire surface section and extending across 45 said transverse depressions or recesses.

2. A furnace grate bar having a fire surface section provided with a series of separated transverse elongated depressions or 50 recesses in its upper face, a slit in each of the depressions or recesses of the fire surface section and extending from the bottom of the depressions or recesses through the under face of the fire surface section, and a 55 plurality of separated longitudinal depressions in said fire surface section and extending across said transverse depressions or recesses.

3. A furnace grate bar having a horizontal fire surface section in its upper face provided with a series of grids separated by elongated and narrow transverse depressions or recesses, a slit in the bottom of each of the depressions or recesses of the fire surface section and extending from the bottom

of the depressions or recesses through the under face of the fire surface section, and a plurality of separate longitudinal depressions in said fire surface section and extending across said transverse depressions. 70

4. A furnace grate bar having a horizontal fire surface section in its upper face provided with a series of grids separated by elongated depressions or recesses in its upper face and arranged transversely to the longitudinal axis of the grate bar, and a slit in the bottom of each of the depressions or recesses of the fire surface section and extending from the bottom of the depressions or recesses through the under face of the fire surface section, and a plurality of separated depressions in said fire surface and extending across said transverse depressions and full length of the grid bar. 80

5. A furnace grate bar having a horizontal fire surface section in its upper face provided with a series of grids separated by transverse elongated depressions or recesses semi-circular in cross section, a slit in and substantially the entire length of each of the depressions or recesses and extending from the bottom of the depressions or recesses through the under face of the fire surface section, and a plurality of separated longitudinal depressions in said fire surface section and extending across said transverse depressions or recesses. 90

6. A furnace grate bar having a horizontal fire surface section in its upper face provided with a series of grids separated by transverse elongated depressions or recesses semi-circular in cross section in a plane passing through the longitudinal axis of the grate bar, a slit in and substantially the entire length of each of the depressions or recesses and extending from the bottom of the depressions or recesses through the under face of the fire surface section, and a plurality of separated longitudinal depressions in said fire surface section and extending across said transverse depressions or recesses. 100

7. A furnace grate bar having a horizontal fire surface section in its upper face provided with a series of grids separated by transverse elongated depressions or recesses arranged transversely to the longitudinal axis of the grate bar and extending to near the side edges of said bar, a slit in the bottom of each of the depressions or recesses and extending from the bottom of the depressions or recesses through the under face of the fire surface section, and a plurality of separated longitudinal depressions in said fire surface section and extending across said transverse depressions or recesses. 110

8. A furnace grate bar having a horizontal fire surface section in its upper face having a spacing projection on each of its sides and provided with a series of grids sepa- 120

rated by transverse elongated depressions or recesses, and a slit in each of the depressions or recesses of the fire surface section and extending from the bottom of the depressions or recesses through the under face of the fire surface section, and a plurality of separated longitudinal depressions in said fire surface section and extending across said transverse depressions or recesses.

10 9. A furnace grate bar having a fire surface section in its upper face provided with a series of grids separated by transverse depressions or recesses, a slit in each of the depressions or recesses of the fire surface
15 section and extending across the upper face and through the under face of the fire surface section, and a heat-conveying rib transversely arranged and depending from the under surface of each of said grids and interposed between the slits separating the grids.

10. A furnace grate bar having a fire surface section in its upper face provided with a series of grids separated by transverse 25 elongated depressions or recesses, a slit in each of the depressions or recesses of the fire surface section and extending across the upper face of the fire surface section and from the bottom of the depressions or 30 recesses through the under face of the fire surface section, and a heat-conveying rib herring-bone in shape transversely arranged and depending from the under surface of each of said grids and interposed between 35 the slits separating the grids.

11. A furnace grate bar having a horizontal fire surface section in its upper face provided with a series of grids separated

by transverse elongated and narrow depre-
sions or recesses, a slit in the bottom of each
of the depressions or recesses of the fire sur-
face section and extending across the upper
face of the fire surface section and from the
bottom of the depressions or recesses
through the under face of the fire surface
section, a heat-conveying rib transversely
arranged and depending from the under
surface of each of said grids and interposed
between the slits separating said grids, and
a plurality of separated longitudinal de-
pressions in said fire surface section and ex-
tending across said transverse depressions or
recesses.

12. A furnace grate bar having a horizontal fire surface section in its upper face provided with a series of grids separated by elongated depressions or recesses arranged transversely to the longitudinal axis of the grate bar, a slit in the bottom of each of the depressions or recesses of the fire surface section and extending across the upper face of the fire surface section and from the bottom of the depressions or recesses through the under face of the fire surface section, a heat-conveying rib herring-bone in shape transversely arranged and depending from the under surface of each of said grids and interposed between the slits separating said grids, and a plurality of separated longitudinal depressions in said fire surface section and extending across said transverse depressions or recesses.

In testimony whereof I hereunto affix my signature.

HOWARD J. WEBSTER.
